Attorney.

UNITED STATES PATENT OFFICE.

GRANVILLE A. HEIMER, OF NAZARETH, PENNSYLVANIA.

GAME APPARATUS.

Application filed January 5, 1927. Serial No. 159,127.

The invention relates to a game apparatus. The object is to provide an improved device for scoring by means of tumblers and means forming an inclined path of travel 5 and various openings and obstructions in the path of said tumblers.

The invention comprises essentially means forming a path or travel surface for the tumblers, slightly inclined to the horizontal, 10 and having certain obstacles projecting above said travel surface, and certain openings in spaced relationship with each other and with said obstacles. One of the said openings is provided with a counterbalanced 15 tilting element having a surface normally in the plane of the said travel surface. Such a tilting device may actuate an effigy or figure which contributes to the spectacular action of the elements.

20 Tumblers are provided, comprising elongated hollow bodies having therein movable and preferably spherical bodies of heavy material, such as lead adapted to move freely from one end of the elongated body 25 to the other and furnishing by momentum an actuating force in causing the tumblers to move down the inclined travel surface. The tumblers are provided with semi-spherical ends to facilitate their movement adapting them to sway or incline sidewise from 30 the perpendicular during their movement and thus to encounter one or another of the obstructions so as to be deflected to the right or left or to be projected into one of the 35 openings as the case may be. The point is that the direction of deflection will depend largely upon the sidewise inclination of the tumbler when it encounters an obstruction.

The device is also provided with a return 40 inclined travel surface to bring the tumblers back to the player and thus facilitate the continuation of the game.

Referring to the drawings which illustrate merely by way of example means for 45 effecting the invention;

Fig. 1 is a view in perspective.

Fig. 2 is a section on line 2, 2 of Fig. 1.

Fig. 3 is a similar view with a pivoted element in tilted position.

50 Fig. 4 is a side elevation of the tumbler on an enlarged scale.

Similar numerals refer to similar parts throughout the several views.

Referring to Fig. 1, the top portion or ex-

tension 6 comprises a flat longitudinal inclined travel surface 7, with the upwardly extending side margins 8. At the lower end of the surface 7 is a transverse substantial perpendicular portion 9, having an aperture 10 in the middle part thereof and extending upwardly from the surface 7. The elements 6, 8 and 9 are shown as supported by the legs 11. The portion of the surface 7 beneath and adjacent to the opening 10 is recessed and provided with the member 12 fitting loosely therein and having its top surface normally in the plane of the surface 7.

This element 12 is pivoted as at 13, and is provided with a weight or counterbalance, 70 as at 23, and with the substantially vertical end 14 for encountering the tumbler and causing the tilting of element 12. The member 15 comprises a travel surface 16 slightly inclined to the horizontal in direction opposite that of surface 7. This element is also supported on the legs 11 and is provided with substantially vertical side margins 17. Element 16 extends beyond the end of surface 7 and is provided with the end flange 75 17' in order to receive the tumblers falling from element 12 and for directing said tumblers back to the end of the device from which they started.

The surface 7 is provided with the obstructions, such as pins 18, and the openings such as 19 through which the tumblers may fall onto the surface 16.

The tumbler 21 is an elongated hollow body made of light material such, for example, as celluloid, or light metal, or similar substance, cylindrical in cross-section and semi-spherical as to its ends. This hollow body is provided with a loosely fitting spherical body 22 of heavy material, such as lead, so that this spherical body may freely move from one end to the other of the hollow body 21. This tumbler 21 is properly dimensioned, and is provided with the spherical body 22 movable therein and of suitable weight to secure the desired tumbling movement on the inclined path 7 provided therefor. That is to say, the dimensions of the hollow body, the weight of the spherical body movable therein, and the degree of inclination of the path of travel, are all factors in securing the desired movement of the tumbler.

In operation: If the tumbler is held in a substantially perpendicular position, as at point 20 on surface 7, and then released, it will travel down the surface toward the lower end of same. It may encounter any of the obstructions or pins 18 or it may fall through either of the openings 19, or it may pass on to element 12 and through opening 10, falling to surface 16 and returning back along said surface to the front of the device. It will, of course, be understood that after the tilting of element 12, to discharge the tumbler on to surface 16, the element 12 automatically returns to initial position with its top surface in the plane of the travel surface 7. The several openings may have arbitrary numbers which may form factors in the scoring.

As the tumbler moves downwardly along the surface 7, it tends to sway from the perpendicular either to the right or the left, as it moves from one end of surface 7 toward the other, and thus, depending upon said inclination, may encounter one or the other of the obstacles and thus be deflected from its direct course of travel. This adds to the hazard of the game.

What I claim is:—

1. In a game apparatus, the combination of means forming an inclined travel surface, having openings and obstacles in spaced relationship with each other, a substantially vertical wall at the lower end of said travel surface provided with an opening extending above said travel surface, a counterbalanced element partly within said upwardly extending opening having its upper surface normally in the plane of said inclined travel surface, and a tumbler for travelling on the inclined travel surface comprising an elongated hollow body provided with a loosely housed spherical weight adapted to roll from one end to the other of the hollow body.

2. In a game apparatus, the combination of means forming an inclined travel surface, having openings and obstacles in spaced relationship with each other, a substantially vertical wall at the lower end of said travel surface provided with an opening extending above said travel surface, a counterbalanced element partly within said upwardly extending opening having its upper surface normally in the plane of said inclined travel surface, means forming a reverse inclined travel surface beneath the first mentioned inclined travel surface, and a tumbler for travelling on said inclined travel surfaces comprising an elongated hollow body provided with a loosely housed spherical weight adapted to roll from one end to the other of the hollow body.

3. In a game apparatus, the combination of means forming an inclined travel surface, having openings and obstacles in spaced rela-

tionship with each other, a substantially vertical wall at the lower end of said travel surface provided with an opening extending above said travel surface, a counterbalanced element partly within said upwardly extending opening having its upper surface normally in the plane of said inclined travel surface, and a tumbler for travelling on the inclined travel surface comprising an elongated hollow body having semi-spherical ends provided with a loosely housed spherical weight adapted to roll from one end to the other of the hollow body.

4. In a game apparatus, the combination of means forming an inclined travel surface, having openings and obstacles in spaced relationship with each other, a substantially vertical wall at the lower end of said travel surface provided with an opening extending above said travel surface, a counterbalanced pivoted element partly within said upwardly extending opening having its upper surface normally in the plane of said inclined travel surface, and a tumbler for travelling on the inclined travel surface comprising an elongated hollow cylindrical body provided with a loosely housed spherical weight adapted to roll from one end to the other of the hollow body.

5. In a game device, the combination of means forming an inclined travel surface having substantially vertical side margins, and having openings and obstacles in spaced relationship with each other, a substantially vertical wall at the lower end of said travel surface provided with an opening extending above said travel surface, a counterbalanced element partly within said upwardly extending opening having its upper surface normally in the plane of said inclined travel surface, and a tumbler for travelling on the inclined travel surface comprising an elongated hollow body provided with a loosely housed spherical weight adapted to roll from one end to the other of the hollow body.

6. In a game apparatus, the combination of means forming an inclined travel surface, having openings and obstacles in spaced relationship with each other, a substantially vertical wall at the lower end of said travel surface provided with an opening extending above said travel surface, an effigy-supporting counterbalanced element partly within said upwardly extending opening having its upper surface normally in the plane of said inclined travel surface, and a tumbler for travelling on the inclined travel surface comprising an elongated hollow body provided with a loosely housed spherical weight adapted to roll from one end to the other of the hollow body.

7. In a game apparatus, the combination of means forming an inclined travel surface, having openings and obstacles in spaced relationship with each other, a substantially

vertical wall at the lower end of said travel surface provided with an opening extending above said travel surface, an effigy-supporting counterbalanced element partly within 5 said upwardly extending opening having its upper surface normally in the plane of said inclined travel surface, and a tumbler for

travelling on the inclined travel surface comprising a properly dimensioned elongated hollow body provided with a loosely 10 housed spherical weight adapted to roll from one end to the other of the hollow body.
